M. R. K. FOWLKES.

WINDOW CLEANER.

APPLICATION FILED DEC. 15, 1913. RENEWED AUG. 26, 1915.

1,163,398.

Patented Dec. 7, 1915.

UNITED STATES PATENT OFFICE.

MARY R. KENT FOWLKES, OF SELMA, ALABAMA.

WINDOW-CLEANER.

1,163,398.

Specification of Letters Patent.

Patented Dec. 7, 1915.

Application filed December 15, 1912, Serial No. 808,844. Renewed August 26, 1915. Serial No. 47,491.

To all whom it may concern:

Be it known that I, MARY R. KENT FOWLKES, a citizen of the United States, residing at Selma, in the county of Dallas and State of Alabama, have invented certain new and useful Improvements in Window-Cleaners; and I do declare the following to be a full, clear, and exact description of the invention, such as will enable others skilled in the art to which it appertains to make and use the same.

This invention relates to improvements in window cleaning devices and has for its object to improve upon the construction thereof to such an extent as to provide a comparatively simple, yet very efficient article.

With these objects in view, the invention resides in certain novel features of construction herein described and claimed; and shown in the drawings, wherein:

Figure 1 is a vertical section of a window frame showing a side view of my improved window cleaner in operation, Fig. 2 is a perspective view, with part of the handle broken off, Fig. 3 is a side elevation partly in section, Fig. 4 is a similar view showing a different arrangement of parts, Fig. 5 is a detail section on line 5—5 of Fig. 2, and Fig. 6 is a perspective view showing another form of the invention.

In the embodiment illustrated in Figs. 1 to 5, inclusive, I have shown a handle 1 having one end flattened at 2, and made slightly wider than its remaining portion, said flattened end being provided with an opening for a purpose to appear.

Straddling the flattened end 2 of the handle 1, are parallel ears 3 formed integral with an adjustable arm 4 carrying a rectangular head 5 on its outer end. A set screw 6 passes through the ears 3, the flattened end 2 of the handle, and is threaded at its free end into a nut 7, washers 8 being preferably provided under the head 9 of the set screw and under the nut 7 to relieve the ears 3 of any unnecessary wear.

The washing element 10 is here shown in the form of a cloth lying over the outer face of the head 5 and having its side and end portions turned down into contact with the sides and ends of said head. When in this position, a clamping band 11 is forced over the folded portions of the cloth and, as clearly shown, will hold them securely in place on the head. One of the longitudinal side bars 12 of the clamping band 11 is pro-

vided on one edge with a U-shaped strip 13 preferably soldered to said edge. A rubber or fabric strip 14 is folded upon itself and has its free edges clamped between the free edges of the U-shaped strip 13, its folded portion projecting beyond the free edges of said U-shaped strip in order to hold the rubber or fabric strip 14 in proper position, I provide lateral flanges 15 and 15' which incase the U-shaped strip 13, and the major part of the rubber or fabric strip 14, the free edges of said flanges terminating a suitable distance from the folded edge of the rubber or fabric strip above mentioned, and lying in yieldable contact with the outer faces of said strip. By this structure, it will be seen that I have provided what is technically known as a "squelgee" for use when drying windows after they have been washed.

By inspection of Figs. 3 and 4, it will be seen that the band 11 is formed of a single sheet of metal so bent as to form a structure U-shaped in cross section, the outer edge of a portion of said band being extended to provide the flange 15 while the flange 15' is secured to the inner edge of a portion of said band and projects in parallel relation to the flange 15, the U-shaped clamping strip 13 being interposed between said flanges 15 and 15' and being soldered along its bend to the inner edge of said band. By this construction, the band proper and the portion thereof constituting the squelgee may be simply and easily manufactured, said band acting not only to retain the washing cloth 10 in position but acting as an attaching means for the squelgee.

In the operation of the device, when it is desired to wash windows, the cloth is placed on the head 5 in the above mentioned manner, and the clamping band 11 is applied in such a manner that the squelgee will face the inactive face of the head 5. The arm 4 may then be adjusted to a suitable angle and the set screw 6 may be tightened to retain the arm and the head 5 in their adjusted position. The lower sash of the window to be washed is now raised and the entire device held on the outside of the window so that the washing cloth contacts with the outer side of the window pane of the upper sash, and by proper manipulation of the cleaner and window sashes, this pane may be washed, the clamping band may be reversed to expose the working face

of the squalgee, and by this means, the window may be readily dried. By proper manipulation of the upper and lower sashes, the pane in the lower sash may be washed and dried in the above mentioned manner.

In the form of the invention shown in Fig. 6 the pivoted arm 4 is replaced by a stationary arm 4', said arm having one of its ends cut at right angles and its opposite end beveled, so as to cause the head 5' to stand at an acute angle to the stationary handle 1' employed with this form of the invention. I preferably provide a second head 5" on the opposite end of the arm 4'.
15 The heads 5' and 5" are of the same dimensions and the clamping band above described is employed in this form of the invention, as well as in the form above described.

20 Although I have described the washing element as comprising a cloth, it will be clearly understood that any suitable washing means could be employed.

From the above described construction, 25 it will be seen that I have produced a very simple, strong, and efficient window washing device, by means of which the outside of windows may be washed while the worker remains on the inside of the building, thus obviating any danger whatever of injury or loss of life.

Having thus described my invention, what I claim is:

1. The combination with a rectangular head, of an elongated rectangular clamping band surrounding the head, said band being U-shaped in cross section, a U-shaped clamping strip secured at its bend to one free edge

of one side bar of the band, a wiping strip U-shaped in cross section and having its free edges secured between the free edges of said U-shaped clamping strip, an integral flange formed on the opposite free edge of said side bar and contacting with one side of the clamping strip and the wiping strip, 45 and a second flange secured to the opposite side portion of said bar, said last mentioned flange contacting with the opposite side of said clamping and wiping strips.

2. The combination with a rectangular head, of an elongated rectangular clamping band surrounding the head, said band being U-shaped in cross section, a U-shaped clamping strip secured along its bend to the free edge of the inner portion of one of the side bars of said band, a wiping strip U-shaped in cross section and having its free edges secured between the free edges of said U-shaped clamping strip, a flange secured to said inner portion of said side bar and contacting with the inner sides of the clamping and wiping strips, and a second flange formed integrally with the outer side portion of said side bar and contacting with the outer sides of said clamping and wiping strips, said flanges lying in parallel spaced relation throughout their lengths and bearing yieldingly against said wiping strip. 60

In testimony whereof I have hereunto set my hand in presence of two subscribing witnesses.

MARY R. KENT FOWLKES.

Witnesses:

RUTH WILLIAMS,
F. A. FOWLKES.
